UNITED STATES PATENT OFFICE.

JUSTIN GILBERT, OF VICTORIA, BRITISH COLUMBIA, CANADA.

SELF-FILLING FOUNTAIN-PEN.

1,108,743.

Specification of Letters Patent. Patented Aug. 25, 1914.

Application filed August 5, 1912. Serial No. 713,399.

To all whom it may concern:

Be it known that I, JUSTIN GILBERT, a subject of the King of Great Britain, residing in the city of Victoria, Province of British Columbia, Canada, have invented certain new and useful Improvements in Self-Filling Fountain-Pens, of which the following is a specification.

My invention relates to apparatus or means for quickly filling a fountain pen by suction through the feed supply duct; one of the objects of my invention being to provide a larger reservoir for the ink than it is possible to secure in any of the other types of self-filling pens without increasing the diameter or length of the ink-holding barrel or reservoir.

My invention consists in forming the ink reservoir of two barrels, one of the barrels fitting within the other telescopically, there being an ink-tight packing between the two barrels to prevent the ink leaking from the reservoir.

In the drawing—Figure 1 is a longitudinal sectional view of a self-filling fountain pen embodying my invention, the parts being shown in normal position; Fig. 2 is a similar view with the parts in abnormal position.

30 A self-filling fountain pen constructed according to my invention is provided with a main barrel 1 and a subsidiary barrel 2, both barrels being open at one end, the subsidiary barrel 2 being telescoped within the main barrel 1.

The main barrel 1 carries at its forward end the pen nib 3 which is suitably secured therein. 4 is a skeleton frame firmly secured in the main barrel 1 near its forward end, 40 from which projects rearwardly an arm 5 provided with a tooth 6 at its rear end disposed at right angles thereto, which is constructed to engage a spiral groove 7 formed in the inner face of the subsidiary barrel 2 as shown.

An ink-tight packing is secured in an annular groove 8 formed in the outer face of the subsidiary barrel 2 near its inner end, and while any suitable packing may be used, 50 I prefer to use a fibrous packing 9 impregnated with graphite, thus providing a permanently lubricated packing between the two barrels mounted upon a soft rubber gasket 9^a which insures a continuous pressure of the fibrous packing against the other barrel, thus maintaining an ink-tight joint between

the two barrels at all times and under all conditions.

It is immaterial as far as my invention is concerned, whether the subsidiary barrel fits 60 within the main barrel or outside thereof.

The tooth or pin which engages the spiral groove acts as a stop to prevent the operator from entirely separating the two barrels.

The subsidiary and main barrels being 65 telescoped, the nib is immersed in ink and the subsidiary barrel pulled outwardly to abnormal position, thus drawing ink in through the feed duct to the extent of the vacuum created by thus extending the length 70 of the ink reservoir. I prefer to have the length of the movement such that the pen is half filled to its entire capacity by the one operation. Then the nib is held upward and the barrels are again telescoped expelling 75 all air from the reservoir, whereupon the intaking of the ink may be repeated as just above described, thus filling the ink reservoir to its full capacity.

Means for preventing accidental telescoping of the two barrels resides in the tooth 80 6 coacting with the spiral groove, and this last means is the preferred construction.

The pitch of the spiral groove is such as to prevent telescopic movement of the two 85 barrels by end to end pressure. The telescopic movement is accomplished only by twisting the barrels relatively and the length of the spiral groove is regulated relatively to the length of the two barrels, so that the 90 end wall of the groove is accurately positioned to serve as an abutment for the tooth 6 to prevent further relative movement between the two barrels.

The subsidiary barrel acts as a piston by 95 reason of the joint formed by the packing between the two barrels.

The ink reservoir feed duct may be quickly cleaned in water by the same movement of the two barrels as in filling with ink.

By my invention, I have eliminated the joint between the feed duct and the main barrel and extended the main barrel to the pen nib, thus simplifying the construction.

By my invention, I provide a self-filling 105 fountain pen of maximum capacity and of very simple construction.

I claim:

1. In a self-filling fountain pen having an ink reservoir composed of two barrels mutually opening into each other and sliding one in the other telescopically for the purpose of

intaking ink, the combination of a spiral groove made inside of one barrel and a frame attached to the other barrel and carrying the stud which fits into the spiral groove and produces the telescopic movement of the two barrels when one is twisted relatively to the other for the purpose of intaking ink, substantially as described.

2. In a self-filling fountain pen having an ink reservoir composed of two barrels mutually opening into each other and slideable one in the other telescopically for the purpose of intaking ink, the combination of a spiral groove formed in the inner face of one of said barrels, and a frame attached to the

other barrel, a stud carried by said frame adapted to fit into said spiral groove and produce a telescopic movement of the two barrels when one is twisted relative to the other, an abutment at the end of said groove 20 against which said stud abuts to prevent the barrels from being accidentally separated.

The foregoing specification signed at Victoria, B. C., Canada, this 25th day of June, 1912.

JUSTIN GILBERT.

In presence of two witnesses—

ROBERT M. NEWCOMB,

EDWARD HUESTIS.
